United States Patent Office

Des. 195,700
Patented July 16, 1963

195,700

INSULATED FOOD AND BEVERAGE CONTAINER

Marten Gottsegen, Chicago, Ill., assignor to Gotham Industries, Inc., Chicago, Ill., a corporation of New York

Filed Nov. 20, 1962, Ser. No. 72,550

Term of patent 14 years

(Cl. D58—17)

FIG. 4

FIG. 5

FIG. 6

FIG. 1 is a front perspective view of an insulated food and beverage container embodying my new design;

FIG. 2 is an end elevational view thereof on an enlarged scale;

FIG. 3 is a rear elevational view thereof;

FIG. 4 is a top plan view thereof;

FIG. 5 is a bottom plan view thereof; and

FIG. 6 is a fragmentary sectional view of a wall thereof, taken on the plane of line 6-6 in FIG. 1 of the drawings.

I claim:

The ornamental design for an insulated food and beverage container, substantially as shown.
